(57) **CLAIM**

We claim the ornamental design for a case for a charger of mobile phone, as shown.

DESCRIPTION

FIG. 1 is a front/left-side/top perspective view of a charger for mobile phone showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a front/left-side/top perspective view thereof showing the aspect when lid is open.

The broken line in FIG. 7 that illustrates a portion of a charging receptacle is directed to environment and forms no part of the claimed design.
